R. W. BURNETT.

DUMP CAR.

APPLICATION FILED SEPT. 11, 1912.

1,096,352.

Patented May 12, 1914.

UNITED STATES PATENT OFFICE.

RICHARD WEBB BURNETT, OF MONTREAL, QUEBEC, CANADA.

DUMP-CAR.

1,096,352.

Specification of Letters Patent.

Patented May 12, 1914.

Application filed September 11, 1912. Serial No. 719,829.

To all whom it may concern:

Be it known that I, RICHARD WEBB BURNETT, a citizen of the United States, residing at the city of Montreal, in the Province 5 of Quebec and Dominion of Canada, have invented certain new and useful Improvements in Dump-Cars; and I do hereby declare that the following is a full, clear, and exact description thereof.

10 My invention relates particularly to dump cars of the type disclosed in my United States Patent application Serial No. 655253, filed October 17th, 1911.

15 My invention consists of the combination of a hopper for a railway car having a door adapted to close to a position in an approximately vertical plane to control the discharge end of the hopper, the hopper having pockets in the end edges of the door 20 opening, a hinge joining the door to the floor of the hopper and comprising a pair of hinge members one of which is formed with a series of alined slots and carried by the floor member, the other having a series of 25 tubular tongues for engagement with the slots and carried by the door, the door having end flanges, the pockets in the door frame receiving such flanges, and clamping devices carried by the door frame and acting 30 upon the free side edge of the door when closed.

The invention further consists of the construction, combination and particular arrangement of parts herein described and 35 pointed out in the claims.

40 For full comprehension, however, of my invention reference must be had to the accompanying drawings forming a part of this specification in which similar reference characters indicate the same parts, and wherein:

Figure 1 is a vertical sectional view of a dump car hopper taken on a line extending transversely relatively to the car; Fig. 2 is an enlarged detail sectional view of the 45 hinge; Fig. 3 is a detail transverse sectional view of one of the flanged ends of the door and the pocket in the door frame engaged thereby taken on line A A Fig. 1; Fig. 4 is a detail elevation of the hopper with the 50 door closed; Fig. 5 is a perspective view of the hinge and portions of the door and hopper floor, the door being thrown open; Fig. 55 6 is a detail elevation of the means for locking the clamping device in position holding the door closed; and Fig. 7 is a detail perspective view of the clamping device.

The hopper floor is indicated at *b* and the ends at *c*, the floor extending from the center sill *d* to within close proximity of the vertical plane of the side sill *e*, thus placing the discharge opening approximately perpendicularly. The dump door *f* is hinged to the floor member and its ends are flanged as at *g* and engage pockets *g'* in the front edges of the hopper ends while the free side edge 60 of the door engages a flange *s* upon the side sill, and it is clamped in its shut position, after having been manually closed, by a rock-shaft *o* carrying a series of dogs *n*. This type of door forms an extension of the 65 floor of the hopper and throws the lading a considerable distance laterally, which is an advantage in that it is thrown clear of the rails. With doors of this type and applied in the manner described to hoppers through 70 which granular commodities are discharged, while the free edges are effectively closed against leakage by the clamping appliance described, the hinged edge has been heretofore a source of trouble owing to leakage 75 due to wear, imperfect fitting, and, in some cases, inherent weakness unless constructed from extra heavy materials.

In order to obviate the defects just described the hinge connection between the 80 dump door and the floor member is effected by a pair of hinge members *p* and *r*. The hinge member *r* is formed with an alined 85 series of slots *u* near its lower edge which is bent downwardly to tubular form, and the hinge member *p* upon the inner edge of the door has a series of tubular tongues *p'* engaging the slots *u*, and a pintle *p²* passed through the tubular edge of the floor and the tubular tongues braces the hinge members 90 in hinged relation and is riveted as at 95 *p³* to the hinge member upon the floor.

A hinge of the form described effectively prevents leakage between the door and hopper floor member, and is strong and durable 100 and of simple construction.

What I claim is as follows:—

1. In a hopper for dump cars, end plates, hopper sills at the opposite sides of the top thereof, an inclined floor member extending 105 from one of said sills to within close proximity of the vertical plane of the other of said sills; a door for closing the opening inclosed by the end plates the floor and the last mentioned sill, and a hinge pivotally connecting the door to the hopper and consisting of a member having a series of 110

alined slots and a member having a series of tubular tongues for engagement with the said slots.

2. In a hopper for dump cars, end plates, hopper sills at the opposite sides of the top thereof, an inclined floor member extending from one of said sills to within close proximity of the vertical plane of the other of said sills; a door for closing the opening inclosed by the end plates, the floor and the last mentioned sill; and a hinge joining the door and the floor member, and consisting of a hinge member having a series of alined slots near one edge thereof, and a hinge member having a series of tongues of open tubular form for engagement with the slots; stiffening flanges upon the said hinged members, means securing one of such hinge members to the floor member and means securing the other hinge member to the door, and means pivotally connecting the said hinge members.
3. In a hopper for dump cars, end plates, hopper sills at the opposite sides of the top thereof, an inclined floor member extending from one of said sills to within close prox-

imity of the vertical plane of the other of 25 said sills; a door for closing the opening inclosed by the end plates, the floor and the last mentioned sill; and a hinge joining the door and the floor member, and consisting of a hinge member having a series of alined 30 slots near one edge thereof, and a hinge member having a series of tongues of open tubular form for engagement with the slots; stiffening flanges upon the said hinged members, means securing one of such hinge members 35 to the floor member and means securing the other hinge member to the door, a pintle pivotally connecting the hinge members, and means preventing displacement of the said pintle. 40

In testimony whereof I have signed my name to this specification in the presence of two witnesses.

Montreal, August 21, 1912.

RICHARD WEBB BURNETT.
